ART OF SEVERING WEBS

William M. Stocker, Hollis, N. Y., assignor to
 Cameron Machine Company, Brooklyn, N. Y.,
 a corporation of New York

Application September 11, 1941, Serial No. 410,481

28 Claims. (Cl. 164—65)

This invention relates generally to the art of severing a running flexible web or sheet into sections, and has more particularly, though not exclusively, reference to the severance of a running web, composed at least in part of thermoplastic material, into sections and to the fusing and sealing of the severed edges of said sections against unraveling.

It is now the custom to divide or sever a web composed of organic derivatives of cellulose, such as acetate, into narrow strips, ribbons or sections and to fuse and seal the severed edges against unraveling. The web can be composed wholly of such derivatives, but frequently it consists in part of other fabric and merely contains a certain amount of yarn, threads or filaments of organic derivatives. In said art, as heretofore practiced, it has generally been the custom to locate a stationary heated severing member in the path of the running web and to thereby sever the web into sections and to fuse and seal the severed edges. It has been found that the severed edges so produced are not smooth and even but are irregular, and that there is a tendency to form blobs or globules which not only detract from the appearance of said sections but render it difficult to properly wind the sections into rolls.

The main object and feature of this invention is to overcome the disadvantages above noted so that the operation of severing and fusing can be carried on at high speeds. Other features of invention will appear as the specification proceeds.

In the accompanying drawings the invention is disclosed in several concrete and preferred forms in which:

Fig. 1 is a view in side elevation of one form of machine for carrying out the invention;

Fig. 2 is a top plan view, looking in the direction of arrow 2 of Fig. 1, with parts broken away and in section;

Fig. 3 is a view, partly in elevation, partly in section and partly diagrammatic of the heated severing member;

Fig. 4 is a vertical sectional view substantially on the plane of line 4—4 of Fig. 3;

Fig. 5 is a longitudinal sectional view substantially on the plane of line 5—5 of Fig. 4;

Fig. 6 is a diagrammatic view of a heated rotatable severing member and a smooth-faced rotatable member that simultaneously engage the running web to sever the same;

Fig. 7 is a plan view of the severed sections to indicate the zones of plasticity and lines of severance produced in the web;

Fig. 8 is a view similar to Fig. 6 but showing the action on a double thickness of web;

Fig. 9 is a perspective view of the product obtained by the action on the double thickness of web;

Fig. 10 is a sectional detail view substantially on the plane of line 10—10 of Fig. 2;

Fig. 11 is a longitudinal vertical sectional view of a modified form of the invention showing more particularly a throw-out or separating mechanism for the heated severing member and the smooth-faced member with which it engages;

Fig. 12 is a view in side elevation of the machine shown in Fig. 10;

Fig. 13 is a top plan view, looking in the direction of arrow 13 of Fig. 11, partly broken away and in section;

Fig. 14 is a detail view of a plurality of heated severing members acting against a plurality of smooth-faced members;

Fig. 15 is a view similar to Fig. 11 but showing still another form of the invention including an automatic throw-out for the severing means;

Fig. 16 is a horizontal sectional view substantially on the plane of line 16—16 of Fig. 15;

Fig. 17 is a vertical sectional view of a machine embodying the invention but showing still another form thereof in that a single smooth-faced member is employed in connection with a plurality of heated severing members and the means that heat said severing members are different from those previously disclosed;

Fig. 18 is a vertical sectional view showing a portion of the machine of Fig. 17 with the parts occupying a different position; and

Fig. 19 is a top plan view, looking in the direction of arrow 19 of Fig. 17, with parts broken away and in section.

Attention is directed first to the disclosure of Figs. 1 to 7 and 10. A running web, consisting at least in part of thermoplastic material (acetate for instance), is indicated at W, and severing means are indicated at 1 and 2. Member 1 is a rotatable, smooth-faced, circular member, here in the form of a roller, and member 2 is a heated and rotatable circular severing member or knife-edged cutting disc having a severing or knife edge 3 beveled in opposite directions (Fig. 6). Member 2 has knife-edge engagement only with web W and member 1, and said members have peripheral speeds in fixed relation to the rate of advancement of the web, i. e. said members rotate at substantially the same surface speed as the speed of the running web, and the rotating movement of both of said members is in the same

direction as the advancing movement of the running web. In the present instance, member 2 is positively rotated by gearing and constitutes a driver for member 1 which latter is rotated by frictional engagement with the former. By subjecting the web to the action of members 1 and 2, there is plasticized by heating, a longitudinal zone, indicated diagrammatically in Fig. 7 by dotted lines 4, that is wider than the line of severance to be made and, simultaneously therewith, there is produced, by the rolling action of members 1 and 2, said line of severance 5 in said zone, intermediate its sides, to thereby convert the web into sections 6 and 6a by severing the non-thermoplastic threads (if any) and to fuse and seal the thermoplastic yarns, threads or filaments of the severed edges. By this method the web is not only converted into sections but the severed edges of said sections are smooth and even and are fused at a progressively diminishing ratio transversely of the line of severance. The reasons for this are that (a) beveled severing edge 3 of member 2 transmits its heat sidewise a considerable distance and renders the thermoplastic material of said zone plastic; because (b) the severed edges of sections 6 and 6a are not distorted out of the plane of said sections, and, further: because (c) the surface speed of members 1 and 2 is substantially equal to the speed of the running web and therefore the fused material is not displaced or disturbed. This is entirely different from a method in which the running web encounters a stationary severing member for, in that case, the severed edges of the sections are brought out of the plane of said sections and a displaced portion of the plastic zone remote from the line of severance could readily become more highly plastic than, or as highly plastic as, the portion immediately adjacent the line of severance. In the instant invention, on the other hand, the plasticity of the material decreases toward the sides of the zone because of beveled severing edge 3, and said zone may even extend sidewise beyond the point where member 2 contacts the web on account of the close proximity to the web of part of those portions of the beveled surfaces of member 2 that are in spaced relation to said web. The angle of bevel of severing edge 3 may vary, but excellent results have been obtained with 45° bevels, that is: a 90° angle between the two bevels, and by slightly dulling, as by stoning, said severing edge.

The degree of heat to be applied to member 2 will depend in part upon the character of the material to be severed and in part upon the speed at which the web material is moved; conversely, the speed at which the material must be moved will depend upon the degree of heat applied to member 2. Generally, the heat should be above the scorching point of the material, and the speed of the web should be great enough to prevent damage to the material. By employing the instant method and the machines herein disclosed, it has been possible to obtain operating speeds of the web up to 120 feet per minute with a fusing temperature of 800° F.

The process is susceptible of use not only to sever a thermoplastic web and to seal the severed edges of the sections so produced, but it can also be employed to produce a tubular article such as is shown in Fig. 9. As indicated in Fig. 8, two superimposed webs W1 and W2, composed at least in part of thermoplastic material, can be passed between members 1 and 2 to thereby si-

multaneously sever the two webs, fuse the severed edges of the sections and fuse the superimposed sections together at their edges W3 into a tubular article W4.

- 5 It is necessary to bring member 2 up to the desired heat before commencing the severing operation and this, in connection with the desirability of threading the web between members 1 and 2 even when member 2 is hot, and
- 10 of bringing the web quickly away from member 2 when the machine stops, creates a problem that is, in the present instance, solved as follows (see particularly Fig. 10): Member 2 has, here, a fixed axis of rotation, but member 1 is rotatably mounted in the bifurcated end of an arm or lever 8 that is pivotally supported on rod or rail 9 which latter can be raised or lowered by a suitable control mechanism here represented by handle 10 and eccentric 11. 12 indicates a
- 15 spring carried by lever 8 and having a tension adjusting screw 13 in abutting engagement with bracket 14 of the frame-work. Lever 8 is located between the side cheeks of a spacer 15 adjustable lengthwise of rail 9 and held in its adjusted position by means of a set-screw 16. 17 and 18 indicate two rotatable guide rollers and it will be observed that these rollers guide the web in a path between members 1 and 2 but somewhat below member 2 when member 1 is in what may
- 20 be called a normal position, i. e. out of engagement with the web and member 2. When member 1 is raised into operating position, it engages the web and bows it slightly to bring it into contact with member 2 under spring pressure of
- 25 spring 12 and, when member 1 is lowered, the spring pressure is relaxed and the advancing web will assume its straight path between guide rollers 17 and 18 to bring said web far enough away from member 2 not to be adversely affected by
- 30 the heat thereof.

Any desired number of members 1 and 2 may be used. Rail 9 extends across the machine and is slidable in vertical guides 19 of the side frames and carries a plurality of members 1 that constitute a set equal in number to the number of members 2. Each member 1 is individually adjustable by means of its arm 8 and spacer 15 as previously described and it will be understood that the raising and lowering of rail 9 moves the entire set of members 1 but that, nevertheless each member 1 will be under its individual spring pressure as determined by adjusting screw 13 associated with each lever 8.

The set of members 2 are here supported on a common rotatable carrier 20 which is essentially a tubular member having a heating element 21, here in the form of resistance wires, the leads 22 of which are connected to collector rings 23 with which latter spring terminals 24 of circuit 25 engage. Members 2 are arranged in properly spaced relation on the exterior of carrier 20 so as to correspond to the position of members 1, and the spacing of members 2 may be changed by interposing between them spacing rings 26 of different widths. Lock nuts 27 in threaded engagement with carrier 20 hold members 2 and spacing rings 26 in position.

Carrier 20 and therefore members 2) is positively driven by any suitable means and constitutes here the main drive of the machine. Members 1 are driven by frictional engagement with members 2 when brought into contact therewith. The means for advancing the web is here shaft 28 of the winding mechanism which advances the web at substantially the same speed as the

surface speed of members 1 and 2, and the web is drawn from web roll 29 over guide roller 30 and thus into the machine. The shaft 31 of web roll 29 may carry a pulley 32 over which passes a brake band 33 to retard unwinding of the web. Power can be derived from any suitable source and can be delivered to the machine through a variable speed mechanism to suit different operating conditions. In the present instance it is preferred to have a variable-speed motor M that by means of a belt 34 drives a pulley 35 concentric, but loose, with respect to carrier 20. A clutch 36 fast with respect to carrier 20 can be slid into and out of engagement with a corresponding clutch surface on pulley 35 to impart rotation to carrier 20 in a well understood manner such as by means of bifurcated yoke 37 pivotally supported at 38 on the framework and having pins engaging in a circumferential groove of clutch 36. Rotating with carrier 20 is a gear 39 that meshes with a gear 40 loose and slidable on shaft 41. Shaft 41 also carries another gear 42 and between gears 40 and 42 are friction surfaces 43, the frictional engagement of which can be adjusted by means of spring 44 and nut 45, the assembly constituting a slip friction drive. Shaft 28 is mounted on one of two arms 46 (one arm on each side of the machine) which arms are adjustable on shaft 41. Shaft 28 carries a pinion 47 that receives its motion from intermediate pinion 48, also mounted on arm 46, and said intermediate pinion 48 meshes with gear 42. Arm 46 is held in its adjusted position on shaft 41 by means of a ratchet 49, stationary on the framework, and a latch 50 pivoted on arm 46. Arms 46 are counterweighted as at 51. In case it is desired to wind alternate severed strips on separate shafts, a second winding shaft 52 can be provided on another pair of arms 53 carried by a shaft 54, and a train of gear and slip friction clutch similar in all respects with that previously described in connection with shaft 28 can be driven from gear 39 to impart movement to shaft 54. In such case alternate strips pass directly from roller 18 to winding shaft 28, and the other alternate strips pass from roller 18 over roller 55 to winding shaft 52. The coils of wound material on shaft 28 are indicated at 56, and those on shaft 52 at 57.

In operating the machine, members 2 are brought up to the requisite heat by closing circuit 25 after control device or throw-out mechanism 10-11 has brought members 1 out of engagement with members 2. The web can be threaded through the machine either before heating the members 2, while they are being heated, or after they are heated. The web is drawn over roller 30, under rollers 17 and 18, between members 1 and 2, and are thence led to one or both winding shafts 28 and 52 as may be desired. When members 2 have been sufficiently heated, clutch 36 is thrown in and members 1 are brought into engagement with the web to bring it against members 2 and to bring smooth-faced members or pressure rollers 1 under sufficient tension to rotate said members 1 at the same speed as members 2 by engagement with members 2. Slip friction drive 43 has previously been adjusted to advance the web at substantially the same speed as the surface speed of members 1 and 2 and, as the diameter of of rewound material increases, slip friction drive 43 can be adjusted by nut 45 to substantially maintain the speed of the web equal to the surface speed of members 1 and 2.

The necessity for keeping the web out of contact with the heated severing member when the machine is not running has already been dwelt upon, and in the form of the invention shown in Fig. 10 it is accomplished by the moving away of the web from the heated severing member. It has been found, however, that, when a high degree of heat is employed, the web has to be moved a considerable distance away from the heated member in order not to have the web adversely affected by the heat, and this creates another problem. The difficulty resides in the fact that the web in moving away from or toward the heated member at times tends to become displaced transversely so that the heated member will not follow the same trace in the web as previously.

To overcome this difficulty, the form of the invention shown in Figs. 11 to 14 has been devised. As there shown, carrier 20a that supports heated members 2a is mounted in slideable boxes 60 that slide vertically in guides 61 in the framework at opposite sides of the machine. Each of these boxes has a pair of upstanding lugs or ears 62 in spaced relation with a pin 63 extending therebetween. Extending across the machine is a rockshaft 64, and this rockshaft carries, at opposite ends, levers 65, each of which has a projection 66 that extends between the pair of ears 62 and is provided with a slot 67 through which pin 63 extends. Levers 65 are connected by an operating handle 68. Rail 9a, for raising and lowering pressure rollers 1a, rests on two carrying arms 69 pivoted at 70 and having their outer ends pivotally connected to the lower ends of rods 71. Said rods 71 are connected at their upper ends to arms 72 of rockshafts 64. It will now be understood that by manipulating handle 68 from the full line position to the dot-and-dash line position of Fig. 11, boxes 60, and therefore carrier 20a and members 2a, will be moved in an upward direction, and rail 9a, and therefore members 1a will be moved in a downward direction. This will leave web W10 practically undisturbed and, in connection with this, attention is called to the fact that guide rollers 17a and 18a have their lower surfaces substantially in line with the lower surfaces of members 2a when boxes 60 are in their lowermost position. Upon a reverse movement of handle 68 of the throw-out mechanism, members 1a and 2a are again brought together without unduly disturbing the web. By the above-described means the heated members 2a can be brought a considerable distance away from the web and the parts can be so articulated that members 2a move a much greater distance in the same period of time than members 1a.

If desired, in order to avoid frequent adjustment of the slip friction drive of winding shaft 28a, two feed rollers 76 and 77 can be interposed between the severing and fusing mechanism and the winding shaft. The upper feed roller 76 is mounted in sliding boxes 78 sliding in guides 79 of the framework and springs 80 normally keep feed rollers 76 and 77 in contact.

Power is, here, applied to shaft 81 by any suitable means either through a variable-speed transmission mechanism or from a variable speed motor. Shaft 81 carries a pinion 82 that meshes with gear 83 on carrier 20a and it will be noted that gear 83 is directly above pinion 82 so that, when said carrier is raised, gear 83 is brought out of mesh with pinion 82. Pinion 82 also drives shaft 84 of feed roller 77 through a train of

gears indicated by 85 and 86, and shaft 84 carries a pinion 87 that meshes with pinion 88 on shaft 89 of feed roller 76. Thus members 1a and 2a are moved substantially at the same surface speed as the speed of the web. Pinion 82 drives shaft 90 through a train of gears indicated at 91, 92 and 93, and shaft 90 carries a sprocket 94 which through sprocket chain 95 drives a sprocket 96 on shaft 97. Shaft 97 carries a gear 98 which through intermediate gear 99 drives gear 100 that through an adjustable slip-friction drive 101 drives winding shaft 28a.

Web W10 is unwound from unwinding roll 29a and passes under guide rollers 30a, 17a and 18a, being advanced by feeding rollers 76 and 77 and thence passes to winding shaft 28a. In its passage between members 1a and 2a the web is severed, fused and sealed in the manner previously described in connection with Figs. 1 to 7 inclusive and 10.

A modification of the form of the invention shown in Figs. 11 to 14 is disclosed in Figs. 15 and 16. In this modification the throw-out mechanism is governed automatically by the speed of the web in such a way that if the machine slows down or stops, members 1a and 2a are automatically separated so as to prevent injury to the web by reason of its contact with heated members 2a. As there shown, levers 65 (and therefore members 1a and 2a) are held in operating position by one or more springs 105. 106 indicates one or more solenoids which, when energized, attract armatures 107 connected to levers 65 thereby overcoming the tension of springs 105 and separating members 1a and 2a as shown in Fig. 15. The circuit for energizing solenoid 106 is indicated diagrammatically at 108 and leads to two contact members 109 insulated from each other. 110 indicates a bridging member carried by speed governor 111 which latter rotates with rotatable guide roller 30a. Web W10 passes under roller 30a and, when the machine is running at the minimum required speed, the rotation of roller 30a and therefore of the speed governor, is sufficient to keep bridging member 110 out of contact with contacts 109. But when roller 30a stops or slows down below the required speed, the spring of the governor will bring bridging member 110 against contacts 109 in a well understood manner, circuit 108 is completed through solenoid 106 and members 1a and 2a are automatically separated. Governor 111 can be rendered ineffective by flexing its arms and holding them in flexed position by means of latch 112 engaging pin 113, should it be desired to do so.

In the forms of the invention hereinbefore described, a set of smooth-faced pressure rollers are employed, and these pressure rollers are movable toward and away from the heated severing members. Turning now to the form of the invention disclosed in Figs. 17 to 19 inclusive, 1b indicates a smooth-faced rotatable cylinder extending across the machine and having a fixed center of rotation, and 2b denotes a plurality of rotatable and heated circular severing members having a severing edge and of a character similar to the severing members previously described. Each severing member 2b is rotatably mounted in the bifurcated end of a pivotally supported arm or holder 114 slidably adjustable on rod 115. Each holder is individually spring-pressed by means of spring 116 having an adjusting screw 117 that bears on a transverse lifting bar 118 slidably mounted in vertical guides 119. Movement of bar 118 in an upward direction swings all the

members 2b downwardly into knife-edge engagement with member 1b under individually adjusted spring pressure. 120 indicates a heater to project a flame directly on members 2b. This heater extends across the machine and is provided with a hood 121 to confine the flame. The heater and hood are mounted on two arms or levers 122 (one at each side of the machine) which are pivoted on a transverse rod 123 carried by the framework. Suitable means are provided to lift and lower bar 118 and to actuate arms 122. In the present instance, a pedal 124 is mounted on rockshaft 125 and carried by this rockshaft are two arms 126, one on each side of the machine. 127 indicates a connecting rod, of which there are two, pivotally connected to arms 126 and bar 118. 128 indicates a connecting rod, of which there are two, pivotally connecting arms 126 and 122. 129 is a transverse bar extending across the machine above holders 114 and is carried by connecting rods 128. A spring 130 tends to urge the pedal in an upward direction, and 131 indicates a latch to hold the pedal in its lowered position after it has been depressed. It will now be understood that, when pedal 124 is depressed, members 2b are brought into contact with member 1b, and that heater 120 is lowered to be in a position adjacent members 2b. Conversely when pedal 124 is released and spring 130 moves it in an upward direction, heater 120 and hood 121 as well as members 2b will be moved in an upward direction, transverse bar 129 as it moves downward assisting by its weight to lift members 2b. It is necessary that members 2b should be brought up to the required heat before the severing and fusing operation begins, and to prevent excessive heat from being applied to part of members 2b, an auxiliary driver is provided in the form of a roller 132 extending across the machine and with which members 2b engage and by which they are rotated when in their upper position out of contact with member 1b. Auxiliary driver 132 is driven by a motor, through belt 133 and pulley 134, independently of the machine so that, when the machine is at rest, members 2b can be rotated and brought up to heat. If desired, a connection to the main clutch (not shown) of the machine can be actuated by the movement of pedal 124. Such a connection is shown at 135 and it will be understood that when pedal 124 is depressed the main clutch is thrown in, and when said pedal is elevated said main clutch is thrown out to stop all of the machine except the auxiliary driver.

Power is applied to shaft 136 carrying pinion 137 meshing with gear 138 mounted to rotate with member 1b whereby said member is rotated, and rotates at the same surface speed, by frictional engagement, members 2b, when the latter are in engagement with member 1b. Gear 138 meshes with gear 139 on shaft 140 and, carried by said shaft, is another gear 141. Interposed between gears 139 and 141 is an adjustable slip friction drive 142. Gear 141 meshes with pinion 143 on winding shaft 28b. 144 indicate two rotatable friction feed rollers, one on each side of member 1b, carried by arms 147 that are pivotally supported at 145 and urged by springs 146 toward said member 1b. 147b indicate stops limiting the movement of said rollers away from member 1b. Web W11, coming from supply roll 29b, passes beneath guide rollers 148 and 149, thence under friction roller 144, around the upper surface of member 1b, thence under the other friction roller 144 and thereafter to wind-

ing shaft 28b. It will be understood that slip friction drive 142 will be adjusted as the diameter of the rewound material increases but, aside from that, the web is in such close frictional contact with member 1b, owing to rollers 144, that it will be moved substantially at the same speed as the surface speed of said member 1b. It will be observed that, by this construction, when the throw-out device, represented by pedal 124 and connections, is actuated and members 2b and the heater are elevated into the position shown in Fig. 18, the web will remain in contact with member 1b and thus will not be disturbed at all. Hence, when members 2b are again lowered into contact with member 1b, they will readily follow the same trace as before. To assure that the web will not be damaged by the heat, member 1b can be a cylinder having a water cooling system indicated by connection 150 so that the web is cooled before, during and after severance. A flexible gas conduit for heater 120 is indicated at 151.

Although the various machines herein disclosed have been described primarily in connection with the process of the instant invention, it is obvious that constructional features of these machines are susceptible of use in other relations and in connection with other processes.

I claim:

1. In a device for severing sheet or web material composed at least in part of thermoplastics, a plurality of rotatable circular cutting elements normally out of cutting relation with said material, means for heating said cutting elements, means for advancing the material to be severed relative to the axis of rotation of said cutting elements, means for rotating said cutting elements with the peripheral speeds thereof in fixed relation to the rate of advancement of said material, a set of individual resilient members, a control means movable from a normal to an operated position and including said individual resilient members for moving said material into engagement with said heated cutting elements to be severed thereat, and means operative by said material advancing means on the movement of said control means from an operating to a normal position to withdraw said material from engagement with said cutting elements.

2. In a device for forming a plurality of strips or ribbons from a web or sheet of fabric material containing yarns, threads or filaments of organic derivatives of cellulose, a set of heated circular knife-edged cutting discs, means for rotating said cutting discs, a set of individually operable pressure rollers one for each of said cutting discs, individual resilient means for operating said pressure rollers to hold said material in engagement with said cutting discs, means for advancing said material relative to said pressure rollers and said cutting discs, and means including said cutting discs and pressure rollers for severing said material as the same is moved relative to said cutting discs and pressure rollers by said advancing means.

3. In a device for forming a plurality of strips or ribbons from a web or sheet of fabric material containing yarns, threads or filaments of organic derivatives of cellulose, a set of heated circular knife-edged cutting discs, means for rotating said cutting discs, a set of individually operable pressure rollers one for each of said cutting discs, individual resilient means for operating said pressure rollers to hold said mate-

rial in engagement with said cutting discs, means for advancing said material relative to said pressure rollers and said cutting discs, means including said cutting discs and pressure rollers for severing said material as the same is moved relative to said cutting discs and pressure rollers by said advancing means, and means for advancing said material at such a rate relative to the peripheral speed of said cutting discs that said cutting discs and pressure rollers have substantially no effect on the advancement of said material.

4. In a device for forming a plurality of strips or ribbons from web or sheet material containing at least in part yarns, threads or filaments of thermoplastics or organic derivatives of cellulose, a plurality of heated circular knife-edged cutting elements, means for moving said material in a direction substantially perpendicular to the rotative axis of said cutting elements, resilient means, a set of pressure rollers one individual to each of said cutting discs operated by said resilient means for pressing said material into knife-edge engagement with said cutting discs, and means including said heated cutting discs and said pressure rollers for severing said material as the same is moved relative thereto by said material moving means.

5. In a device for forming a plurality of strips or ribbons from web or sheet material containing at least in part yarns, threads or filaments of thermoplastics or organic derivatives of cellulose, a plurality of heated circular knife-edged cutting elements, means for moving said material in a direction substantially perpendicular to the rotative axis of said cutting elements, a set of pressure rollers one individual to each of said cutting discs for pressing said material into knife-edge engagement with said cutting discs, means independent of said material for driving said cutting discs and pressure rollers, means including said heated cutting discs and said pressure rollers for severing said material by a rolling severing action as the same is moved relative thereto by said material moving means and means for advancing said material at such a rate relative to the direction and peripheral speed of said cutting discs that said rotating cutting discs have substantially no effect on the advancement of said material.

6. In a device for forming a plurality of strips or ribbons from web or sheet material containing at least in part yarns, threads or filaments of thermoplastics or organic derivatives of cellulose, a plurality of heated knife-edged severing elements, means for moving said material relative to said severing elements and means operative during the advancement of said material by said last mentioned means to bring the same into only knife edge engagement with said severing elements to be severed thereby.

7. In a device for forming a plurality of strips or ribbons from web or sheet material containing at least in part yarns, threads or filaments of thermoplastics or organic derivatives of cellulose, a plurality of heated rotatable circular knife-edged severing discs, means for moving said material relative to said severing discs, individual resiliently operable means associated with each of said severing discs and means including said last mentioned means for holding said material in engagement with only the knife edges of said severing discs to be severed thereby during advancement thereof by said material moving means.

8. In a device for forming a plurality of strips

or ribbons from web or sheet material containing at least in part yarns, threads or filaments of thermoplastics or organic derivatives of cellulose, a plurality of heated knife-edged cutting discs, said discs being maintained at a temperature above the scorching temperature of said thermoplastics or organic derivatives of cellulose in said material, resiliently operated means for bringing said material into only knife edge engagement with said cutting discs and advancing the same therewith at such a rate as to prevent scorching of said material by said heated cutting discs, and means including said heated cutting discs upon engagement with said material for severing the same by cutting action of the yarns, threads or filaments in said material of other than thermoplastics or organic derivatives of cellulose if present and by melting and cutting action of said yarns, threads or filaments of thermoplastics or organic derivatives of cellulose in said material.

9. In a device for forming a plurality of strips or ribbons from web or sheet material containing at least in part yarns, threads or filaments of thermoplastics or organic derivatives of cellulose, a plurality of heated knife-edged cutting discs, said discs being maintained at a temperature above the scorching temperature of said thermoplastics or organic derivatives of cellulose in said material, an independently pivotable member associated with each of said cutting discs, means including said members for bringing said material into only knife edge engagement with said cutting discs and advancing the same therewith at such a rate as to prevent scorching of said material by said heated cutting discs, and means including said heated cutting discs upon engagement with said material for severing the same by cutting action of the yarns, threads or filaments in said material of other than thermoplastics or organic derivatives of cellulose if present and by melting and cutting action of said yarns, threads or filaments of thermoplastics or organic derivatives of cellulose in said material.

10. In a device for severing a web of substantial width composed at least in part of thermoplastic material into a plurality of ribbons or strips of narrow width, a set of circular rotatable knife-edged cutting discs adjustably arranged along a common axis, means for heating said cutting discs, individual pressure rollers one associated with each of said cutting discs carried on individual arms pivotally and adjustably mounted on a common axis substantially parallel to the axes of said cutting discs, individual resilient means for biasing said arms to hold said pressure rollers in engagement with associated cutting discs, means for advancing the web to be severed relative to said pressure rollers and cutting discs and in a direction substantially perpendicular to the axes thereof, means comprising said pressure rollers for holding the web in knife edge engagement with said cutting discs whereby said discs perform a cutting action on said web and liquefy the thermoplastic material adjacent the individual edges of the severed strips, and means for rotating said discs at such a speed relative to the rate of advancement of said web that the engagement of said web with said discs is a rolling engagement.

11. In a device for severing a web of substantial width composed at least in part of thermoplastic material into a plurality of ribbons or strips of narrow width, a set of circular rotatable knife-edged cutting discs adjustably arranged

- along a common axis, means for heating said cutting discs, individual pressure rollers one associated with each of said cutting discs carried on individual arms pivotally and adjustably mounted on a common axis substantially parallel to the axes of said cutting discs, individual resilient means for biasing said arms to hold said pressure rollers in engagement with associated cutting discs, means for advancing the web to be severed relative to said pressure rollers and cutting discs and in a direction substantially perpendicular to the axes thereof, means comprising said pressure rollers for holding the web in knife edge engagement with said cutting discs whereby said discs perform a cutting action on said web and liquefy the thermoplastic material adjacent the individual edges of the severed strips, means for rotating said discs at such a speed relative to the rate of advancement of said web that the engagement of said web with said discs is a rolling engagement, and means including the adjustment of said pressure rollers and cutting discs along their respective axes for severing strips of various widths from said web.
12. In a device for severing a web of substantial width composed at least in part of thermoplastic material into a plurality of ribbons or strips of narrow width, a set of circular rotatable knife-edged cutting discs adjustably arranged along a common axis, means for heating said cutting discs, individual pressure rollers one associated with each of said cutting discs carried on individual arms pivotally and adjustably mounted on a common axis substantially parallel to the axes of said cutting discs, individual resilient means for biasing said arms to hold said pressure rollers in engagement with associated cutting discs, means for advancing the web to be severed relative to said pressure rollers and cutting discs and in a direction substantially perpendicular to the axes thereof, means comprising said pressure rollers for holding the web in knife edge engagement with said cutting discs whereby said discs perform a cutting action on said web and liquefy the thermoplastic material adjacent the individual edges of the severed strips, means for rotating said discs at such a speed relative to the rate of advancement of said web that the engagement of said web with said discs is a rolling engagement, and means for pivoting the arms carrying said pressure rollers to move the same and said web out of severing engagement with said cutting discs irrespective of the operation of said web advancing means.
13. The method of smoothly severing a running flexible web, composed at least in part of thermoplastic material, into longitudinal sections and sealing the severed edges thereof without distorting said edges out of the plane of said sections, which consists in: subjecting said web to the simultaneous action of two members, one, a rotatable, smooth-faced circular member and, another, a heated and rotatable, circular severing member, both of said members having a rotating movement in the same direction as the advancing movement of the running web and both members having substantially the same surface speed as the speed of the running web.
14. In a web severing machine, a rotatably driven smooth-faced, circular member, friction rollers at opposite sides of said member to train a web in frictional contact around a portion of the surface of said member to thereby advance said web at a speed substantially equal to the surface speed of said member and a rotatable

circular severing member, located intermediate said friction rollers, to engage and sever said web as it passes around said first-mentioned member and driven from the latter by frictional knife-edge contact therewith at substantially the same surface speed as that of said first-mentioned member.

15. In a web severing machine, a rotatably driven smooth-faced, circular member, means to train a web in frictional contact around a portion of the surface of said member to thereby advance said web at a speed substantially equal to the surface speed of said member, a rotatable circular severing member to engage and sever said web as it passes around said first-mentioned member and driven from the latter by frictional knife-edge contact therewith at substantially the same surface speed as that of said first-mentioned member, means to circulate a cooling medium through the interior of said first-mentioned member, means to heat the exterior of the severing member, and means to move the severing member out of contact with said first-mentioned member.

16. In a web severing machine, a rotatably driven smooth-faced, circular member, means to train a web in frictional contact around a portion of the surface of said member to thereby advance said web at a speed substantially equal to the surface speed of said member, a rotatable circular severing member to engage and sever said web as it passes around said first-mentioned member and driven from the latter by frictional knife-edge contact therewith at substantially the same surface speed as that of said first-mentioned member, means to circulate a cooling medium through the interior of said first-mentioned member, means to heat the exterior of the severing member, means to move the severing member out of contact with said first-mentioned member, and means to rotate said severing member when out of contact with said first-mentioned member.

17. In a web severing machine, a rotatably driven smooth-faced, circular member over the surface of which a web to be severed passes, a rotatable circular severing member to engage and sever said web and driven from the latter by frictional knife-edge contact therewith, means to move said severing member out of contact with said first-mentioned member, a heater to heat the exterior of said severing member both when in or out of contact with said first-mentioned member, and an auxiliary driver to rotate the severing member independently of said first-mentioned member.

18. In a web severing machine, a rotatably driven smooth-faced circular member over the surface of which a web to be severed passes, a rotatable circular severing member to occupy either of two positions, one in contact with and another out of contact with said first-mentioned member, a heater to heat said severing member before the latter engages said first-mentioned member and to continue to heat said severing member after the latter engages said first-mentioned member, and means to move said severing member into engagement with said first-mentioned member.

19. In a web severing machine in which two rotatable members engage each other to sever a web passing therebetween and in which one of said members drives the other, means to cause said members to engage or disengage one another, and heater means to heat one of said mem-

bers whether or not they are in or out of engagement.

20. In a web severing machine, a rotatably driven smooth-faced circular member over the upper surface of which a web to be severed passes, a rotatable circular severing member pivotally supported above said first-mentioned member, a heater pivotally supported above the severing member, and control means and connections to move said severing member and said heater on their pivotal supports toward and away from said first-mentioned member.

21. In a web severing machine, a rotatably driven smooth-faced circular member over the upper surface of which a web to be severed passes, a rotatable circular severing member pivotally supported above said first-mentioned member, a heater pivotally supported above the severing member, control means and connections to move said severing member and said heater on their pivotal supports toward and away from said first-mentioned member, and a clutch operating element for said first-mentioned member associated with the control means and connections aforesaid and moving therewith.

22. In a web severing machine: a rotatably driven smooth-faced member, a rotatable web severing member driven by knife-edge contact with said smooth-faced member, a heater for heating the surface of said web severing member, means to move said web severing member out of contact with the smooth-faced member while retaining a heating relation between the heater and said web severing member, and an auxiliary driver to engage and rotate the web severing member when the latter is out of contact with the driven smooth-faced member.

23. In a web severing machine in which a heated rotatable web severing member engages with a smooth-faced rotatable member, heater means to project a flame against the surface of said web severing member, and connections to move said web severing member and said heater means in unison away from the smooth-faced member.

24. In a severing machine for a running flexible web, a rotatable severing device between the members of which the web passes, comprising: a rotatable smooth-faced circular member and a rotatable heated severing member having knife-edge contact with said first-mentioned member, both of said members having substantially the same surface speed as the speed of the running web.

25. In a web severing machine for a running flexible web in which two members engage to lengthwise sever the running web, throw-out means to bring said members out of engagement, a roll driven by the running web, and a speed-controlled device driven by said roll to render the throw-out means effective to bring said members out of engagement when the speed of the roll falls below a certain point.

26. In a web-severing machine in which a running web is severed lengthwise by the cooperation of two rotatable members, one a smooth-faced circular member and the other a circular severing member having knife-edge engagement with said first-mentioned member, guiding means to direct the web between the two members, and throw-out mechanism to move both of said members toward or away from each other to engage or disengage the web substantially simultaneously without substantially disturbing the web from its path to thereby enable the severing member

when engaging the web after having been separated therefrom to follow substantially the same trace that it previously followed.

27. In a machine for severing a running web, composed at least in part of thermoplastic material, into sections and sealing the severed edges of said sections, means to advance the web, severing means, composed of two rotatable members between which the web passes, to plasticise, by heating, a longitudinal zone in said running web, said zone being wider than the line of severance to be made, and to simultaneously produce a line of severance in said zone intermediate its side without distorting the edges thus severed out of the plane of said sections, means to heat one of said members, and means to rotate said members in the same direction as the advancing

movement of the web and at substantially the same surface speed as that of the running web.

28. In a machine for severing a running web, composed at least in part of thermoplastic material, into longitudinal sections and sealing the severed edges of said sections, means to advance the web, severing means composed of a rotatable, smooth-faced circular member and a heated and rotatable, circular severing member between which members the web passes, means to heat said circular severing member, and means to rotate said members in the same direction as the advancing movement of the web and at substantially the same surface speed as that of the running web.

WILLIAM M. STOCKER.
